UNITED STATES PATENT OFFICE.

JAMES T. FENTON, OF SALT LAKE CITY, UTAH.

PROCESS OF CRACKING AND DISTILLING OIL.

1,394,481.

Specification of Letters Patent.

Patented Oct. 18, 1921.

Application filed May 1, 1920. Serial No. 378,216.

To all whom it may concern:

Be it known that I, JAMES T. FENTON, a citizen of the United States, residing at Salt Lake City, in the county of Salt Lake and 5 State of Utah, have invented certain new and useful Improvements in Processes of Cracking and Distilling Oil, of which the following is a specification.

The present invention relates to a highly 10 simplified method of cracking oils for the production of oils of lower boiling points and lower molecular weights. The invention is applicable to the treatment of various kinds of oils, either mineral oils containing 15 paraffins alone or those containing paraffins and other bodies, such as asphalts, or oils containing aromatic substances, such as crude creosote, crude naphthalenes, etc., for the production of benzene (C_6H_6 which 20 latter substance is to be clearly distinguished from "benzin," a product of petroleum).

In the system of cracking or breaking up the molecular structures of various organic substances (contrary to most of the accepted 25 principles of the processes heretofore proposed), the cracking or breaking up is not produced by keeping the material to be cracked, and the cracking or distilling medium apart, but in this system the cracking 30 and distilling medium, superheated steam, is mixed directly with the material to be cracked and distilled and kept in a state of constant motion and agitation, so that in 35 passing through the various portions of the apparatus, the heat of the steam is brought into more intimate contact with the oil under treatment, and the effectiveness of the heat supplied is very greatly enhanced. In the system, the production of coke is entirely 40 eradicated, there being no coke and no free carbon produced at any stage of the process, since the oil and the steam are maintained in a constant state of agitation, whereby no destructive distillation can be 45 produced.

A feature of great importance in connection with the process is that through the interaction of the steam and the oil, such 50 contents of crude oil as the natural aromatic gums, etc., will be effectively separated from the lighter fractions (for example gasolene) since the former occupies a point of condensation far above that of the gasolene. From this it follows that the 55 gasolenes produced in accordance with my

invention will require practically no refining, and hence the expense of refining and the "refining loss" are both avoided.

Another important feature of the invention is that the oils are cracked and distilled 60 in their entirety and instantaneously, except the heavy portions of the oil, such as paraffin wax, cylinder stock, etc., which it is desired not to crack.

Apparatus in accordance with the present 65 invention is illustrated diagrammatically in the annexed drawings forming a part of this specification, but it is to be understood that these drawings show one modification only, and that the invention is not limited 70 to the particular embodiment of the invention illustrated in the drawings.

In said drawings, Figure 1 shows a diagrammatic side elevation (parts in section) of an entire apparatus suitable for use in 75 the present process. Fig. 2 shows, on a somewhat larger scale, the preferred construction of the cracking chambers, and their connections.

Fig. 3 is a cross section of the chamber, 80 showing the spiral vanes, and Fig. 4 is a detail view.

Referring more particularly to the detailed construction shown in the drawings, oil is introduced through the oil feed pipe 85 10 into a preheater 11, in which the oil is warmed up, but not vaporized. The warm oil passes through pipe 12 into a mixer 13, which it will be noted is in the form of an injector, high temperature superheated 90 steam being introduced through pipe 14. The mixture of oil and superheated steam pass through the pipe 15 into the first cracking chamber 16 in which the oil is instantaneously vaporized, or vaporized all 95 except the heaviest constituents, which as above noted, it is desired not to crack. From the first cracking chamber the vaporized oil, together with unvaporized fractions, pass through pipe 17 into the mixer 100 18, where it is again mixed with high pressure superheated steam from the pipe 19. The mixture flows through pipe 20 into a second cracking chamber 21, in which the cracking operation is completed. The resulting 105 gases and vapors flow through pipe 22 into the settling and separating tank 23 where they are expanded. A baffle 24 is preferably located a short distance in front of the outlet of the pipe 22, in order to thor- 110

oughly mix and commingle the vapors and in order to assist in the separation of the heavy constituents of the oil, which are not to be cracked.

5 The heavy constituents are drawn off in liquid form through the valved outlet trap 25 and the remaining gases and vapors pass off through pipe 26, into a series of condensers 27, 28, 29 and 30, in which the 10 various grades of oil condense, the least volatile portion condensing in the condenser 27, another portion, say light spindle oils collecting in the condenser 28, kerosene condensing in the condenser 29 and gasoline condensing in the condenser 30. The resulting gases containing light vapors then pass to a rhigolene condenser 31, in which the gases and vapors are preferably cooled to such as extent as to condense the rhigolene. The remaining gases and vapors containing substantial amounts of ethylene and other hydrocarbons of the olefin series pass off through the pipe 32 into the sulfuric acid absorbers 33, in which the ethylene is converted into ethyl sulfuric acid, and other gaseous olefins are converted into the corresponding acid products.

20 The vapors issuing at 34 may then be compressed and cooled for the purpose of 30 collecting cymogene.

In the above example, I have described particularly the treatment of a petroleum oil, but I wish it to be understood that in place of a crude petroleum, a petroleum distillate can be employed for example kerosene, solar oil, gas oil or the like, and if desired, also crude creosotes or crude naphthalenes may likewise be treated for the production of benzols C_6H_6 , and other aromatics.

40 By referring to Figs. 2 and 3, it will be noted that the cracking receptacle 16 is provided with a heavy heat insulating layer 36, and that inside of this receptacle there is 45 provided if desired a vane or ridge 38 of any desired height, for the purpose of giving a whirling motion to the gases and vapors therein. While it is not absolutely necessary that such vane or projection be provided, it is advisable to provide the same in 50 order to more thoroughly mix and commingle the oil vapor and superheated steam. The superheated steam supplied by pipes 14 and 19 is under high pressure and is highly 55 superheated, in order to produce and maintain the necessary heat and pressure in the cracking retorts.

60 The entire cracking operation is carried out under a superatmospheric pressure and 65 at a high temperature. The temperature in the first cracking chamber may be from 500 to 700° F., and the temperature in the second may be from 700 to 1000° F., and the pressure in the first chamber 65 may be from 20 to 50 pounds per

square inch, and in the second cracking chamber may be from 50 to 80 pounds per square inch. Each particular grade of oil is best treated at a particular temperature, which is found in practice to be most advantageous for that particular grade of oil to produce just the desired extent of cracking and no more.

70 The pressure and temperature are maintained at the point necessary with each particular oil to regulate and control the degree of cracking. Accordingly, it is not possible to give any particular statements of exact pressure and temperatures to be employed.

75 It is to be noted that all of the heat and all of the pressure are supplied by means of the superheated steam introduced through the pipes 14 and 19, and it is not necessary to pass the oil vapor or the oil 80 while undergoing decomposition through coils or chambers located in furnaces which operation has been heretofore usually considered essential in oil cracking, and this has been open to the objections of producing 85 considerable quantities of coke or hard carbon, by a far-reaching cracking operation. Such production of coke is entirely avoided in the present case, by avoiding the unnecessary high heats and the valuable portions of the oil under treatment which would 90 be cracked in this manner are thereby saved.

95 The oil preheater 11 may in some cases be dispensed with. However, I find it advisable to preheat the oil to a temperature of, say, 100 to 150° C., or in any event, to not over 175 to 200° C., before the same is first treated with the superheated steam. This operation is for the purpose of imparting some heat to the oil without any danger of 105 cracking before the same enters the process. The oil entering pipe 12 may be at about atmospheric pressure or a slight pressure may exist due to the head of oil coming from the oil tank which may be located 110 at a higher level. This amount of pressure, however, is negligible and may be disregarded for the purpose of the present invention.

115 In connection with the advantages of the system of cracking oil, as hereinabove described, I call attention to the feature that all of the oil cracking is produced simultaneously as distinguished from numerous prior processes which have been proposed in 120 which the cracking is produced fractionally or in a number of successive stages. Also it is particularly noted that in operating upon a crude oil or an oil left after distilling off some of the lighter fractions, it 125 is advisable not to crack the cylinder stock, which is of much greater value than gasoline. In ordinary cracking of petroleum oils, in accordance with the present invention the idea is to produce as much as pos- 130

sible of the gasoline or petroleum ether fractions with the production of a minimum of the other materials present.

- A further advantage to be noted is that 5 the apparatus does not have to be operated continuously to prevent "freezing up," since there are no accumulations of heavy materials to freeze up in the plant if allowed to go cold. For stopping the process it is necessary only to shut off the feed of oil, allow steam to blow through the apparatus for a few minutes and the whole plant will be clear and clean and the flow of steam can then be cut off and the plant allowed to cool. 10 15 Similarly, in starting operations, it is necessary only to blow steam through the apparatus for a short time in order to pre-heat it and then after the working temperature has been reached, turn on the oil feed 20 and the cracking operation begins at once, thereby it being readily possible, starting from a cold apparatus, to have the cracking process under way at full capacity in from 20 to 30 minutes. 25

A feature of importance is the instant and absolute control of the ratios of steam and oil, depending upon the particular kind of oil treated.

The process involves the law which may 30 be expressed as follows "the boiling point of mixed liquids which do not dissolve in each other is determined by their combined vapor pressures. When the combined vapor pressures is equal to the external pressure both 35 liquids will distil."

It is advisable, as shown in Fig. 2 of the drawing, to make the rear ends of the chambers (or the ends opposite to the intake of the vapor to the chambers) renewable, since 40 the friction of the oil vapor and steam pounding against these bottoms may wear out the same in a relatively short time, or much before the normal wearing out of the other portions of the apparatus. It is, in 45 many cases, also advisable to place the baffle plate 40 in each of these chambers as illustrated in Fig. 2, so that the vapors and gases will impinge upon this baffle plate 40 which may be readily renewable. If de- 50 sired, the baffle plate 40 may be given any desired shape in order to produce a rotary or whirling action of the gases and vapors in the chambers, so as to produce more complete mixing. For this purpose, a plate with a 55 spirally grooved cone center may be useful, as shown at 40^a in Figs. 3 and 4.

I have above referred to, the absence of extraneous heating by furnaces and the like, such as common in the prior patents, which 60 have been issued in this art.

The ethylene sulfuric acid produced in the sulfuric acid absorption apparatus as well as the other members of this series can be used for the production of alcohols, by appropriate treatment with water, so that al-

cohol may constitute a by-product of the process.

I desire to call particular attention to the fact that in my process, it is advisable to so adjust the temperature, pressure, proportion of steam and other factors that the high boiling products, such as paraffin, vaseline and cylinder stock will not, at least to any substantial extent, be cracked, since these materials are of higher value than the 75 lighter products which would be produced by such cracking. The cracking is accordingly, largely effected in the kerosene, solar oil and gas oil fractions; and the heavier products, as well as the gasoline present, are 80 merely distilled. The fractions above stated, which are cracked in the present process, are the products which at the present time are 85 of low value, relatively to the cylinder oil, paraffin and gasoline.

In the drawing, I have shown four condensers, 27, 28, 29 and 30. It is, of course, to be understood that the number of condensers may be greatly increased, if desired, thus for example, instead of using four only, I might 90 employ ten or more of such condensers, depending upon the number of separate products which are to be recovered from a given treatment. The temperature of the several condensers will be controlled by suitable 95 cooling baths, so that the products condensed therein will, usually without further refining, be suitable for placing on the market.

In a modified form of operation, the temperatures employed in the various steps of 100 the process may be so adjusted that the operations which go on will be principally distilling, without any substantial amount of cracking. For this, low temperatures will 105 usually be employed in the vessels 16 and 21.

No claim is made herein to the apparatus hereinbefore described and shown in the accompanying drawings as claims thereto are made in my application for Patent No. 438,977, filed Jan. 21, 1921.

I claim:

1. The hereinbefore described process of treating oils which consists in cracking or disrupting the molecular structure of the oils by heat supplied solely by the direct contact of superheated steam under pressure with said oils while in a subdivided and agitated condition and while continuously flowing from a source of supply toward a condenser; so controlling the heat and pressure of the superheated steam as to crack a portion of the constituents of the oil, passing the cracked and uncracked constituents to a separator, there expanding and separating said constituents, drawing off the heavier 115 fractions, and then progressively condensing the lighter fractions of the product.

2. The process hereinbefore described of treating oils which consists in mixing the oil with superheated steam under pressure, sub-

110

115

120

125

130

dividing and agitating the oil while in direct contact with the steam and while under pressure in a cracking chamber, passing all of the products of the first chamber to a similar second chamber, there subjecting the contents of the second chamber to the direct action of a second supply of steam at a higher temperature and under greater pressure, causing the oil and steam to flow continuously from a source of supply toward a condenser, so controlling the heat and pressure of the steam as to crack a portion of

the constituents of the oil, passing all of the constituents to a separator, there expanding and separating the uncracked constituents from the others, and then condensing the lighter fractions of the product; the heat and pressure for the cracking operation being supplied solely by the superheated steam under pressure, substantially as described. 15 20

In testimony whereof, I have hereunto subscribed my name.

JAMES T. FENTON.
